UNITED STATES PATENT OFFICE.

JOHN DU BOIS, OF WILLIAMSPORT, PENNSYLVANIA.

IMPROVEMENT IN BUILDING FLUMES FOR FLOATING LOGS

Specification forming part of Letters Patent No. 41,285, dated January 19, 1864.

To all whom it may concern:

Be it known that I, JOHN DU BOIS, of Williamsport, in the county of Lycoming and State of Pennsylvania, have invented a new and Improved Mode of Building Flumes and Preparing Small Streams for Floating Logs and other Lumber; and I do hereby declare that the following is a full, clear, and exact description thereof, reference being had to the accompanying drawings, making a part of this specification, in which—

Figure 1 is a top view of one section of my improved flume crossing the bend in a stream. Fig. 2 is a vertical longitudinal section through Fig. 1. Fig. 3 is a vertical transverse section through Fig. 1. Fig. 4 is a perspective view of the sill and upright supports for the flume-trough. Fig. 5 is an end elevation of the flume-trough shown in Fig. 1.

Similar letters of reference indicate corresponding parts in the several figures.

This invention relates to certain new and useful improvements in the construction and arrangement of flume-troughs which are used for floating large or small logs of timber from one place to another through the country, thus transporting them to marketable places from the places where they were cut by a very easy and comparatively inexpensive method. In some sections of the country, where timber is plenty and remote from navigable rivers, logs and other lumber are frequently transported from one place to another by means of narrow flumes laid level with the surface of the ground, which communicate at their source with a dam of water. By letting water into the flume-troughs it will float the logs therein, and they will thus follow the course of the stream to the extent to which the flume may be carried.

The object of my invention is to construct these flumes in such a manner that logs will not be obstructed in passing through the same, and also so that small logs may be floated in them with a comparatively small quantity of water, thereby obtaining a great saving of water, besides obviating a great difficulty hitherto experienced in keeping the stream clear and the logs continually in motion.

It further has for its object preventing the flume from injury by high water at points where the flume crosses a stream, and also the damming of the natural bed of the stream at such crossing-points in such a manner that

while I can pass off the surplus water down the stream when it is swollen I am also enabled to force the escape-water into the flume when the water in the stream becomes low, all as will be hereinafter described.

To enable others skilled in the art to make and use my invention, I will proceed to describe its construction and operation.

In order to give a clear understanding of one part of my invention, it will be necessary to imagine a narrow trough set into the ground and extending for miles through the country, and at certain points we will imagine this trough or flume crossing a stream which is serpentine in its course. The drawings, Fig. 1, represent one bend of a stream over which the flume A passes, and the arrows indicate the direction of the currents both in the stream and in the flume.

The flume box or trough is constructed of five planks, *a a a*, which give five sides to it, the bottom plank being in a horizontal plane and the two uppermost planks being arranged in vertical planes, while the other two side planks incline inward, as shown clearly in Figs. 3 and 5. The framing to which these planks are nailed consists of a timber, *b*, which is placed under the flume-box, and also two upright pieces, *c c*, which are notched on this sill *b*, as shown in Fig. 4. These latter pieces are cut so that their edges form supports for the inclined and vertical side boards of the flume, and to these pieces, sill, and side supports the flume-boards are nailed. It has been the practice hitherto to mortise and tenon the sills and side supports of square flumes together; but this mode of framing is objectionable, chiefly on account of the time and expense required in performing the work, especially so when each section of flume requires several of these frames. By notching the lower ends of the side pieces, *c c*, on the sill and then bolting them firmly thereto, as shown in the drawings, the shoulders resting on the sill forms a perfect brace, and when applied to the flume and firmly embedded in the earth this framing forms a perfect wing in the embankment to prevent the water that may escape through the flume-trough or that coming in from the hillsides from washing the embankments and allowing the water that may escape to form a new channel, and thus render the flume useless on this account. Then, again,

in places where the flumes are used it is not always convenient to obtain means for mortising, and it is much more convenient and easier to cut this framing out in a circular-saw mill. These upright supports *c c* being formed, as shown in Fig. 4, I obtain a very wide base-support, which greatly increases the strength of the flumes and dispenses with cross-braces for resisting lateral strain or expansion. Such braces are always more or less in the way of large logs, and it is desirable to dispense with them. My framing leaves the top part of the flume entirely open, and no obstruction is offered to large logs floating down.

The square or rectangular flumes are objectionable, on account of the large quantity of water which is required to float logs in them. This is especially the case in floating small-sized logs. To obviate this objection, and to obtain a saving of water, I cut off the lower corners of the flume, and by thus contracting the bottom of the flume I diminish its capacity for containing water without diminishing its capacity for receiving and floating round logs.

The flume is supposed to cross the stream B at many points, and at each crossing I erect small dams of a peculiar construction, the objects of which are to conduct off the surplus water from the stream into the flume, and to prevent injury to the flume when the stream is swollen. On each side of the stream, at the crossing-points, I firmly embed in the earth strong timbers *g g*, which extend transversely across the flume and project suitable distances from each side thereof. The tops of these timbers extend up a short distance above the top edges of the flume, and the bottom of these timbers extends some distance below the bottom of the flume, so as to form a passage, *h*, Fig. 2, for the water in the stream B to escape. On the "lower" side of the chute, or under channel *h*, I arrange a gate, *k*, which extends

up to the top of the sides *g g* of this chute and down to the bed of the same.

It will be seen from this description that I am enabled to check the current of the stream over which the flume crosses by closing the gate *k*, and thus conduct the water from the stream into the flume, and when the stream is swollen the gate *k* can be partially or wholly opened, so as to allow the surplus water to escape through the channel which is formed beneath the flume.

By this arrangement the gates, at each point where the stream is crossed by the flume, can be so adjusted as to pass off all the surplus water in the natural bed of the stream, thereby securing the flume from injury by high water, and controlling the whole when the water is low. The flume-trough being constructed with inclined sides, it will be seen that it will offer less obstruction to the passage of the water under it at the crossing-points than if it were made in the form of a square box. This gives me another important advantage in the use of my polygonal flume for floating round logs.

Having thus described my invention, what I claim as new, and desire to secure by Letters Patent, is—

1. Providing for the passage of water under the flume A and into the flume A at the points where the flume crosses streams, substantially as and for the purpose described.

2. A log-floating flume constructed with an under-and overflow channel and gate, arranged over a stream, substantially as and for the purpose set forth.

Witness my hand in matter of my application for a patent for building flumes and preparing small streams for floating and driving logs and other lumber.

Witnesses: JOHN DU BOIS.
